UNITED STATES PATENT OFFICE

149,305

DESIGN FOR A SWEATER

John Rosenfeld, Philadelphia, Pa.

Application September 4, 1946, Serial No. 133,043

Term of patent 3½ years

(Cl. D3—4)

To all whom it may concern:

Be it known that I, John Rosenfeld, a citizen of the United States, residing at Philadelphia, in the county of Philadelphia and State of Pennsylvania, have invented a new, original, and ornamental Design for a Sweater, of which the following is a specification, reference being had to the accompanying drawing, forming part thereof.

The figure on the drawing is a front view of a sweater, showing my new design.

The ornamentation on the front of the sweater is repeated on the back, the sleeves being plain and unornamented.

I claim:

The ornamental design for a sweater, substantially as shown and described.

JOHN ROSENFELD.
